(57) **CLAIM**

The ornamental design for a twistable and connectable block, as shown and described.

DESCRIPTION

FIG. 1 is a front, perspective view illustration of a twistable and connectable block according to the present invention;

FIG. 2 is a back, perspective view illustration of the twistable and connectable block depicted in FIG. 1;

FIG. 3 is a front, perspective view illustration of a first half of the twistable and connectable block depicted in FIG. 1;

FIG. 4 is a front, perspective view illustration of a second half of the twistable and connectable block depicted in FIG. 1;

FIG. 5 is a top, perspective view illustration of the first half of the twistable and connectable block as depicted in FIG. 3;

FIG. 6 is a bottom, perspective view illustration of the first half of the twistable and connectable block as depicted in FIG. 3;

FIG. 7 is a front, view illustration of the first half of the twistable and connectable block as depicted in FIG. 3;

FIG. 8 is a left, view illustration of the first half of the twistable and connectable block as depicted in FIG. 3;

FIG. 9 is a bottom, view illustration of the first half of the twistable and connectable block as depicted in FIG. 3;

FIG. 10 is a right, view illustration of the first half of the twistable and connectable block as depicted in FIG. 3;

FIG. 11 is a rear, view illustration of the first half of the twistable and connectable block as depicted in FIG. 3;

FIG. 12 is a top, view illustration of the first half of the twistable and connectable block as depicted in FIG. 3;

FIG. 13 is a top, perspective view illustration of the second half of the twistable and connectable block as depicted in FIG. 4;

FIG. 14 is a bottom, perspective view illustration of the second half of the twistable and connectable block as depicted in FIG. 4;

FIG. 15 is a front, view illustration of the second half of the twistable and connectable block as depicted in FIG. 4;

FIG. 16 is a left, view illustration of the second half of the twistable and connectable block as depicted in FIG. 4;

FIG. 17 is a bottom, view illustration of the second half of the twistable and connectable block as depicted in FIG. 4;

FIG. 18 is a right, view illustration of the second half of the twistable and connectable block as depicted in FIG. 4;

FIG. 19 is a rear, view illustration of the second half of the twistable and connectable block as depicted in FIG. 4; and,

FIG. 20 is a top, view illustration of the second half of the twistable and connectable block as depicted in FIG. 4.
